(57) **CLAIM**

The ornamental design for a basket for an appliance, as shown and described.

DESCRIPTION

FIG. 1 is a perspective view of a basket for an appliance showing our new design, it being understood that the pattern on the cylindrical wall of the basket repeats around the circumferential direction of the cylindrical wall as also shown in FIGS. 3, 4, 5 and 6.

FIG. 2 is a front view of the basket for an appliance.

FIG. 3 is a side view of the basket for an appliance it being understood that the pattern on the cylindrical wall of the basket repeats around the circumferential direction of the cylindrical wall.

FIG. 4 is another side view of the basket for an appliance it being understood that the pattern on the cylindrical wall of the basket repeats around the circumferential direction of the cylindrical wall.

FIG. 5 is another side view of the basket for an appliance it being understood that the pattern on the cylindrical wall of the basket repeats around the circumferential direction of the cylindrical wall.

FIG. 6 is another side view of the basket for an appliance it being understood that the pattern on the cylindrical wall of the basket repeats around the circumferential direction of the cylindrical wall.

FIG. 7 is rear view of the basket for an appliance; and,
FIG. 8 is a front view of the basket for an appliance with a rim
removed from the front of the basket to further reveal the
interior components thereof.
